UNITED STATES PATENT OFFICE

159,902

CLOCK CASE OR SIMILAR ARTICLE

Leon Glosband, Swampscott, Mass.

Application June 29, 1948, Serial No. 147,278

Term of patent 7 years

(Cl. D42—7)

To all whom it may concern:

Be it known that I, Leon Glosband, a citizen of the United States residing at Swampscott, in the county of Essex, State of Massachusetts, have invented a new, original, and ornamental Design for a Clock Case or Similar Article, of which the following is a specification, reference being had to the accompanying drawing, forming part hereof.

In the drawing:

The figure is a front perspective view of a clock case or similar article, showing my new design, the back of the same being conventional.

I claim:

The ornamental design for a clock case or similar article, substantially as shown and described.

LEON GLOS BAND.
